GRAPPLE FORK LOCK AND HEAD

William H. Zehner, Ashland, Ohio, assignor to
The F. E. Myers & Bro. Co., Ashland, Ohio, a
corporation of Ohio

Application October 22, 1936, Serial No. 106,947

13 Claims. (Cl. 294—109)

This invention relates to grapple forks, and particularly automatic grapple forks.

It is an object of this invention to provide in a grapple fork a lock and head construction wherein in the opening and closing of the fork may be controlled from a remote station by means of a trip rope.

It is a further object of this invention to provide in such a grapple fork a lock construction 10 provided with lock levers having cam surfaces adapted, when the lock is drawn upwardly toward the head by means of a trip chain, to engage complementary surfaces on the head construction to securely lock the lock member to the head member, whereby to permit of the closing of the 15 fork by gravity.

It is a further object of this invention to provide a head construction adapted to be supported as desired and a lock construction adapted to support the tines of the fork, the tines being connected by flexible members to arms on the head construction and the lock being adapted to be released from and engaged with the head construction by means of a trip chain extending 20 through the head construction.

It is a further object of this invention to provide a lock construction wherein pivotal support is provided for the tines of the fork and wherein a pair of pivotally supported lock levers are 25 adapted to cooperate with a slidable cam bar, said cam bar being resiliently urged toward a position for engagement with said lock levers to urge the lock levers outwardly.

It is a further object of this invention to provide such a construction wherein complementary cam surfaces are provided on the lock levers and the cam bar.

It is a further object of this invention to provide such a construction wherein the cam bar is 40 connected to a trip chain by means of which the cam bar may be withdrawn from engagement with lock levers by tension on the trip chain.

It is a further object of this invention to provide in such a construction cam surfaces on the 45 lock levers adapted to engage cam surfaces on the head construction to swing the lock levers inwardly sufficiently to permit interpenetration of the lock and head.

It is a further object of this invention to provide further surfaces on the lock levers adapted, 50 when the tension on the trip chain is released subsequent to interpenetration of the lock and head members, to cooperate with surfaces of the head member to support the lock therein.

55 These and other objects and advantages will

appear from the following description taken in connection with the drawings.

In the drawings:

Figure 1 is a view in perspective of the grapple fork in closed position; 5

Figure 2 is a similar view of the grapple fork in opened position;

Figure 3 is an enlarged fragmentary view in elevation of the structure shown in Figure 2;

Figure 4 is an enlarged top plan view of the 10 head member of my construction;

Figure 5 is an enlarged section taken on the line 5—5 of Figure 4, showing the preliminary engagement of the lock member with the head member; 15

Figure 6 is a view similar to Figure 5, but showing the lock lever means of the lock member in attracted position;

Figure 7 is a second view, similar to Figure 5, but showing the lock member locked to the head 20 member;

Figure 8 is a section taken on the line 8—8 of Figure 5;

Figure 9 is a side elevational view of the lock member; 25

Figure 10 is a similar view, in section, taken along the line 10—10 of Figure 8;

Figure 11 is a section taken on the line 11—11 of Figure 6;

Figure 12 is a section taken on the line 12—12 30 of Figure 5;

Figure 13 is a view in perspective of one of the lock levers; and

Figure 14 is a view in perspective of the cam bar. 35

Referring to the drawings in detail, as seen particularly in Figures 1 and 2, the head member, generally designated 1, is adapted to be supported by attachment to the fork pulley of a hay carrier or by means of a rope, cable, chain or the like 2 which is secured to the loop portion. The head member 1 is provided with outwardly extending arms, to which are attached tine support chains 3, each of which has the other end thereof attached to a tine support arm 4 which is suitably connected to a tine construction including a plurality of tines 5, which is pivotally supported by the lock member 6. 40

The lock member 6 is provided with a pair of lock levers which are constantly urged outwardly 50 by a cam bar which is supported within the lock member and resiliently urged in a position to press the lock levers outwardly. The cam bar 26 has a loose connection with the body of the lock member. A trip chain 7 extends from the cam 55

bar upwardly through the head member 1. The trip chain is provided with an enlarged ring at one end to which a suitable trip rope may be attached for remote control of the lock member.

5 In Figure 1 the grapple fork is shown in closed position, and in that position the tension being removed from the trip chain 7, the lock member 6 is secured in a manner hereinafter more clearly described by engagement of the lock levers there-
10 of with a suitable flange in the head member 1. The opposed complementary tine constructions are pivotally supported by the lock member 6 and, sufficient slack being provided in the tine support chains 3, the complementary tine construc-
15 tions are urged together by gravity and the weight of the load when the hay grasped by the grapple fork is lifted by means of a rope or cable 2.

After the loaded grapple fork has been moved to the desired position above the mow or other 20 place where it is desired to deposit the load from the loaded grapple fork, tension is placed on the trip chain 7, whereby to cause the lock member 6 to be released from the head member 1 whereby the parts take the position illustrated in Figure 2.

25 As shown in Figure 2, when tension is released from the trip chain 7, the head 1, by means of the arms thereon which are connected by means of tine support chains to the tine support arms 4, supports the weight of the lock and comple-
30 mentary tine constructions, the location of the tine support arms 4 and the length of tine support chains 3, as well as the proportions of the remaining structure being carefully chosen for correct balance.

35 After the hay has been deposited, as described above, in the desired location, tension is placed upon the trip chain 7 and the parts locked, as indicated in Figure 1. The parts remain in this 40 position, while the grapple fork is returned to the hay supply. This locking of the fork prevents injury to workmen by contact with the sharp points of the tines 5. When the grapple fork, locked as shown in Figure 1, reaches the hay supply, the operator grasps each side of the fork simultaneously and sinks the tines into the hay.

45 The details of the above generally described head member 1 and lock member 6 are as follows: the head member 1 (Figures 3 to 8 inclusive) comprises a unitary casting provided with a loop member 11 at the top thereof, providing means for attachment of the fork pulley of a hay carrier or of a supporting rope, cable or the like to the head member and therebelow is formed an annular portion 12 having the sides thereof cut away 50 and terminating at the bottom in an annular flange 13 having a substantially horizontal upper surface 14 and a substantially inclined lower surface 15. Extending outwardly of the annular portion and formed integrally therewith are op-
55 positely disposed arms 16 which are provided at their ends with suitable bores 17 by means of which the above referred to tine support chains 3 are attached to the head member, generally designated 1. A trip chain guideway 18 is formed in 60 the head member 1 and extends from centrally above the flange 13 to one side of the head member just below the loop 11.

65 The lock member 6 comprises a casing formed of a pair of complementary members 19 provided with inwardly extending substantially U-shaped flanges 20 and each having a pair of bosses 21 disposed at opposite sides of the upper portion thereof, the flanges and bosses being adapted to be engaged when the members 19 are secured together to form a casing. These members are pro-

vided with suitable apertures adapted to receive the upper or cam guide pin 22 and lower or lock lever pintle pin 23 by means of which the complementary members 19 are secured together to form a housing or casing.

5 Centrally disposed in each of the members 19 is a recess 24 which extends longitudinally or vertically and each of which is adapted to receive and house a compression spring 25. The cam guide pin 22 is adapted to extend through an elongated slot 27 in the cam bar 26. The cam bar has enlarged cam portions 28 disposed at opposite sides of the elongated slot 27 and spring steps 29 extending from opposite sides of the cam bar 26. Above the cam portion 28 of the cam bar 26 is 15 a bifurcated apertured portion 30 which is adapted to receive a trip chain attaching pin 31 for the attachment of a trip chain 7 thereto. The lower portions 28a of the cam surfaces 28 are inclined inwardly for a purpose which will herein-
20 after more clearly appear.

With reference particularly to Figures 6, 9, 10 and 14, it will be seen that the cam bar 26 is slidably supported by means of engagement of the elongated slot 27 with the cam guide pin 22 25 and by the disposition of the spring steps 29 in the respective recesses 24. The springs 25 are supported in the recesses 24 with one end thereof in engagement with a top wall of the recess and the other end thereof resting upon a spring step 30 29 of the cam bar 26. By means of this arrangement, the cam bar 26 is constantly resiliently urged downwardly by means of the springs 25 in the recesses 24. The springs 25 need possess only sufficient strength to return the cam bar 35 26 to position between the two lock levers 32; and, therefore, it is merely necessary that their strength be sufficient to overcome the friction between the cam bar 26 and the two lock levers 32.

40 Pivotedly supported on the lock lever pintle pin 23 by means of apertures 33 is a pair of similar oppositely disposed lock levers 32 which have the body portion thereof offset from the aperture 33 thereof, and each of which has, formed at the upper end thereof, a projection 34 which is provided with an inwardly and upwardly disposed cam surface 35 adapted for engagement with the portion 28a of the cam portion 28 of the cam bar 26, as shown in Figure 6, and an arcuate cam surface 36 extending outwardly and 50 downwardly therefrom, which is adapted to engage the surface 15 of the flange 13, as shown in Figure 5. The projection 34 terminates in a substantially flat locking surface 37 which is adapted to engage the surface 14 of the flange 55 13, as shown in Figure 7. The inner longitudinal surfaces of the lock levers 32 are adapted to be engaged by opposite cam surfaces 28, as shown in Figure 5.

60 Outward swinging movement of the lock levers 32, under the influence of the cam bar 26, is limited by the flanges 20 on the members 19. Each of the members 19 is provided below the flange 20 thereon with a circular aperture 39 which is adapted to support a pintle pin 40. Slightly 65 above and spaced at opposite sides of each aperture 39 is an aperture 41. The apertures 41 are adapted to receive pins 42 similar to the pin 22 for securing the lower portions of the members 19 in rigid spaced relation. The tines 5 are suitably apertured for pivotal support on the pintle pin 40. The tines may be secured to the pintle pin 40, either inside of or outside of the lower portions of the members 19. The tines 5 have been illustrated as supported between the lower 75

end portions of the members 19 in Figures 1, 2 and 3 for the sake of clearness of illustration.

Operation

5 The cooperation of the head member 1 and lock member 6 with the other parts of the grapple fork has been described above. The cooperation of the lock member 6 with the head member 1 is as follows: when the parts are in 10 the position illustrated in Figure 2 and the trip chain 7 is released from tension, the parts of the lock member 6 will be in the position shown in Figure 5. In this position of parts, the force of the springs 25, which act upon the spring steps 15 29 of the cam bar 26, retains the flat cam surfaces 28 in engagement with the inner flat surfaces of the lock levers 32. This prevents inward movement of the cam levers 32. If tension is placed upon the trip chain 7, the lock member 20 6 may be brought upwardly into the position illustrated in Figure 5, wherein the surfaces 36 engage the surface 15 of the flange 13 of the head member 1. The above described position of the cam bar 26 prevents inward swinging movement 25 of the lock levers 32 until the cam surfaces of the cam bar 26 are removed from between the lock levers 32, as shown in Figure 6.

When the flat cam surfaces of the cam bar 26 are removed from between the lock levers 32, the engagement of the arcuate cam surfaces 35 with the surfaces 15 draws these lock levers 32 inwardly until they reach the position shown in Figure 6. This is all accomplished by the application of tension to the trip chain 7 and the progressive upward movement of the lock member 6 and the progressive inward swinging movement of the lock levers 32, due to the engagement of cam surfaces 36 with surfaces 15 and cam surfaces 28a with cam surfaces 35 occurring substantially simultaneously. After the parts have reached the position illustrated in Figure 6, a slight further upward movement of the lock member 6 places the locking surfaces 37 of the lock levers 32 above the surfaces 14 of the flange 13.

45 If the tension on the trip chain 7 is now released, the springs 25 will urge the cam bar 26 downwardly whereby the engagement of the surfaces 28a of the cam bar 26 with the cam surfaces 35 of the lock levers 32 will cause the lock levers to move outwardly until they take the position 50 illustrated in Figure 7, wherein it will be seen that the flat cam surfaces 28 of the cam bar 26 again engage the inner flat surfaces of the lock levers 32 whereby to securely lock the lock member 6 to the head member 1.

In order to unlock the lock member 6 from the head member 1, tension is again placed upon the trip chain 7 whereby to draw the cam bar 26 upwardly against the pressure of springs 25 to permit the lock levers 32 to swing inwardly to the position illustrated in Figure 6, whereupon, upon release of the tension upon the trip chain 7, the projections 34 of the lock levers 32 will pass downwardly through the central aperture surrounded by the flange 13, whereby to unlock 65 the lock member 6 from the head member 1.

The fork is so balanced that it can be returned from the position shown in Figure 2 to that shown 70 in Figure 1 by exerting only a slight pull on the trip chain 7 and after the lock and the center of the fork passes above the center of gravity, when the trip chain is pulled to close the fork, the lock will be supported and urged upwardly toward the head member by the counterbalancing effect of

the weight of the tines 5. The tension of the springs 25 preferably being such that they will barely support the weight of the lock assembly, a slight pull of the trip chain 7 acting upon the cam bar 26 moves the cam bar 26 upwardly so 5 that the lock levers 32 move inwardly toward each other by reason of the bevel surfaces 28a on the cam bar 26 and the bevel or cam surfaces 35 on the lock levers 32. When the fork is loaded and the parts are in the position shown in Figure 10 7, the slight taper of the upper surface 14 of the flange 13 on head member 1 and the slight taper of the cooperating surfaces 37 of the lock levers 32 results in the lock levers 32 being urged toward each other by weight of the fork and load upon 15 release of the cam bar so as to allow the projections 34 of the lock levers 32 to pass downwardly through the central opening in the annular flange 13 of the head member 1 in order that the tines may be opened to dump the load. 20

It will be understood that the above described structure is merely illustrative of one manner in which the principles of my invention may be utilized and that I desire to comprehend within my invention such modifications as come within 25 the scope of the claims and the invention.

Having thus fully described my invention, what I claim as new and desire to secure by Letters Patent is:

1. In a grapple fork provided with a plurality 30 of tines, a head member comprising lateral extensions, and connections between the extensions and the tines, a locking member having locking devices to interconnect and disconnect the head member and the locking member, said plurality 35 of tines being pivotally supported on said locking member, and tension means connected to said locking member for closing said tines.

2. In a grapple fork provided with a plurality 40 of tines, a head member comprising lateral extensions, and connections between the extensions and the tines, a locking member having locking devices to interconnect and disconnect the head member and the locking member, said plurality 45 of tines being pivotally supported on said locking member, and tension means connected to said locking member for closing and locking said tines.

3. In a grapple fork, a head member and a locking member adapted to be engaged to close 50 said fork, and spring actuated lever means for interconnecting said members, said locking member having locking means adapted, upon engagement of said members, to cooperate with means on said head member to interlock said members 55 in engagement, and a cam means to control the locking movements of the locking means.

4. In a grapple fork, a head member and a locking member adapted to be engaged to close 60 said fork, and tension means for engaging said members, said locking member having locking means adapted, upon engagement of said members, to cooperate with means on said head member to automatically lock said members in engagement, said locking means being responsive 65 to said tension means for unlocking said locking member from said head member.

5. In a grapple fork, interpenetrating head and locking members adapted for engagement to close 70 said fork, and means for engaging said members comprising a trip chain connected to said locking member and extending through said head member, said members having means adapted upon engagement automatically to lock said members together.

6. In a grapple fork, interpenetrating head and locking members adapted for engagement to close said fork, and means for engaging said members comprising a trip chain connected to said locking member and extending through said head member, said members having means adapted upon engagement automatically to lock said members together, said last-named means being responsive to tension on said trip chain to unlock said members.
7. In a grapple fork having a plurality of tines, a head member connected to said tines, a locking member adapted for engagement with said head member and having said tines pivotally supported thereon, and means for simultaneously closing and locking said fork comprising a tension member connected to said locking member and extending through said head member.
8. In a grapple fork having a plurality of tines, a head member connected to said tines, a locking member adapted for engagement with said head and having said tines pivotally supported thereon, means for simultaneously closing and locking said fork including a tension member connected to said locking member and extending through said head member, and normally operative locking means in said locking member adapted automatically to lock said head and locking members together upon engagement.
9. In a grapple fork having a plurality of tines, a head member connected to said tines, a locking member adapted for engagement with said head and having said tines pivotally supported thereon, means for simultaneously closing and locking said fork including a tension member connected to said locking member and extending through said head member, and normally operative locking means in said locking member adapted automatically to lock said head and locking members together upon engagement, said locking means in said locking member being adapted to be made inoperative by said tension member to release said locking member from said head member.
10. In a grapple fork having a head member provided with a flange, a locking member adapted to pivotally support fork tines, said locking member having a body supporting for limited sliding movement cam means normally biased in one direction, lock means adapted to be projected from said body by said cam means when biased, and tension means connected to said cam means adapted to support said body through said cam means and release said cam means from said lock means.
11. In a grapple fork having a head member provided with a flange, a locking member adapted to pivotally support fork tines, said locking member having a body supporting for limited sliding movement cam means normally biased in one direction, lock means adapted to be projected from said body by said cam means when biased, and tension means connected to said cam means adapted to support said body through said cam means and release said cam means from said lock means, said lock means being adapted under the influence of said cam means to engage the flange on said head member and being adapted upon release of said cam means therefrom to be disengaged from said flange.
12. In a grapple fork including a head member having thereon flange means, a locking member having a cam bar mounted for limited sliding movement therein, resilient means for normally biasing said cam bar in one direction, a pair of lock arms provided with outwardly directed end projections mounted for outward swinging movement under the influence of said cam bar when biased, and a trip chain connected to said cam bar and extending through said head and adapted, when placed under tension, to release said cam bar from said lock arms and engage said locking member with said head member, and adapted when thereafter released to allow engagement of said cam bar with said lock arms for engagement thereof with the flange on said head member.
13. A grapple fork comprising a head member having supporting arms and flange means, a locking member having a cam bar mounted for limited sliding movement therein, resilient means for normally biasing said cam bar in one direction, a pair of lock arms mounted for outward swinging movement under the influence of said cam bar when biased and provided with outwardly directed end projections, a pair of tine assemblies pivotally supported on said locking member, a chain connecting each of said tine assemblies with an arm of said head, and a trip chain connected to said cam bar and extending through said head adapted, when placed under tension, to release said cam bar from engagement with said lock arms while engaging said locking member with said head member and adapted when thereafter released to permit engagement of said cam bar with said lock arms whereby the projections on said lock arms will be engaged with the flange on said head member to lock said head member and said locking member together.

WILLIAM H. ZEHNER. 55
